UNITED STATES PATENT OFFICE.

HENRI PERROT, OF ALEXANDRIA, SCOTLAND, ASSIGNOR TO ARGYLLS LIMITED, OF ALEXANDRIA, SCOTLAND.

BRAKE.

1,076,311.

Specification of Letters Patent.

Patented Oct. 21, 1913.

Application filed January 14, 1913. Serial No. 742,047.

To all whom it may concern:

Be it known that I, HENRI PERROT, a citizen of the French Republic, and residing at Alexandria, Dumbartonshire, Scotland, have invented a certain new and useful Improvement in Brakes, of which the following is a specification.

This invention relates to brakes for road vehicles and it consists in the combination 10 of elements and features of construction hereinafter particularly described and pointed out in the claims whereby the pull on the brake-actuating rods is taken diagonally from the hubs of the front road 15 wheels to the hubs of the rear road wheels, so that liability of side slip is avoided while the steering of the vehicle is unaffected by the braking.

In the accompanying drawings Figure 1 20 is an elevation and Fig. 2 is a plan, partly in section, showing the chassis of a motor road vehicle embodying the invention; Fig. 3 is a detail view of one of the hub brakes; Figs. 4 and 5 show details of the brake-controlling mechanism; Fig. 6 shows a detail of the hand brake-controlling lever; Fig. 7 is a vertical section of one of the front road 25 wheels fitted with brake devices including a universal joint; Fig. 8 is a plan of the 30 parts of the universal joint taken asunder; Fig. 9 is a plan of a spherical ball of the joint showing grooves therein.

Referring to the drawings, the hub of each of the front and rear road wheels of 35 the vehicle is provided with a brake drum A adapted to be engaged internally by brake shoes B, Figs. 1 and 3, which shoes are pivotally mounted on a pin C and arranged to be moved outwardly, against the action of 40 springs G, as by means of the rectangularly-shaped end portion D of a rotatable spindle E to which is fixed an arm F, so as to cause the shoes B to engage the rim of the brake drum, the arms F being all operatively connected to a foot lever H and to a hand lever I. The said foot lever H is freely mounted on a cross shaft J and pivotally connected to the foot lever H at K is a double-armed 45 differential or compensating lever L, Figs. 1, 2 and 4, which is slotted at both ends. One slotted end of the lever L engages with a pin M on one arm of a bell-crank lever N secured to the cross shaft J and connected by means of a pull rod O to the arm F 50 adapted to actuate the shoes of the brake on

the right hand front road wheel P. Also secured to the cross-shaft J, adjacent the end remote from the bell-crank lever N, is a toothed sector Q, Figs. 2 and 5, which is constantly in mesh with a correspondingly toothed sector R pivoted at S and forming part of a bell-crank lever connected by means of a pull rod T to the corresponding arm F for actuating the shoes of the brake on the left hand rear road wheel U. The other slotted end of said lever L engages with a pin V on a double-armed lever W secured to one end of a tubular shaft X coaxial with, and freely mounted in relation to, the cross shaft J, one end of said lever W terminating in a toothed sector Y, Figs. 2 and 4, constantly in mesh with a correspondingly toothed sector Z pivoted freely on a fixed shaft at a and forming part of a bell-crank lever b which is connected by means of a pull rod c to the corresponding arm F for actuating the shoes of the brake on the right hand rear road wheel d, the corresponding brake on the left hand front road wheel d¹ being similarly actuated by 70 means of a pull rod e connected at one end to an arm x fixed to the tubular shaft X at the end thereof remote from that to which the lever W is fixed.

The hand lever I for controlling the brakes 85 is freely mounted on the shaft a and is movable relatively to a quadrant f, which quadrant is provided with teeth g adapted to be engaged by a manually-controlled catch device h, the boss of said lever I and the boss 90 of the bell-crank lever b being in engagement with one another after the manner of a one-way clutch whereby all the brakes may be operated either by hand or foot, the lever I serving to maintain the brakes in engagement, by reason of the catch device h connected therewith engaging the teeth of the quadrant f.

To allow for the movement of the front road wheels in steering, the articulation in 100 each of the corresponding brake-actuating spindles E is made, in the vicinity of the brake drums, as at E¹ and E², in the form of a universal joint having its center arranged to coincide with the point of intersection of 105 the axes of the rectangularly shaped pin portion D and the adjacent steering wheel pivot m.

The universal joint at E¹ and E² may comprise, as shown in Figs. 7 to 9, a spheri- 110

cal ball *i* having circumferential grooves *j* which intersect each other, as shown in Fig. 9. One of said grooves *j* is freely engaged by the forked or bifurcated outer end *D*¹ of the pin *D* which engages the brake shoes *B*, while the other groove *j* is engaged by a similar fork *E*¹¹ on the adjacent end of the spindle *E*. The engaging parts of the joint are held together by an outer casing *k* which is secured to lugs on the plate *l* carrying the steering wheel pivot *m* and which is suitably slotted at *n* for the passage of the spindle *E*. The slot *n* may be covered to exclude dust by means of a concavo-convex washer *p* mounted on the spindle *E* and adapted to slide upon the exterior surface of the casing in the vicinity of the slot. The inner end of the spindle *E* is connected up to its corresponding brake-operating arm *F* on the chassis so that it may slide or rock relatively thereto within certain limits to accommodate the movement of the vehicle springs. For this purpose the inner end of the spindle *E* may pass through an aperture *g* in the frame of the chassis and be provided with a spherical collar *r*. This collar may be mounted loosely on the spindle *E* and is located in a bearing *s* of corresponding shape secured to the frame of the chassis. The spindle *E* may be left free to slide through the collar *r* while the brake-operating lever *F* is keyed to the projecting inner end of said spindle *E*, as shown in Fig. 7.

As shown in Figs. 2 and 6, the boss of the hand lever *I* is formed with a gap entered by a projection *t* extending from the boss *u* of the bell-crank lever *b*, the face *v* of said projection normally engaging a corresponding face *v*¹ on the boss of the hand lever *I* and clearance being afforded at *w*, whereby the hand lever *I* may impart rotary movement to the shafts *J* and *X*, through the intermediary of the toothed sectors *Z*, *Y*, levers *W*, *L*, and *N* and relative connections, and thereby apply the brakes; while the clearance at *w* permits the opposite face *y* on the projection *t* to be brought against, or in close proximity to, the face *z* on the boss *u*, when the brakes are applied by means of the foot lever *H* and relative connections, whereupon the hand lever *I* may be moved in the direction of the arrow, Fig. 6, relatively to the quadrant *f*, as aforesaid, until the face *v* on said projection is engaged by the corresponding face *v*¹ on the boss *u*, the brakes being thus maintained in engagement. It will be understood that when the foot lever is actuated, the hand lever is not disturbed, the clutch members moving apart. It will of course be understood that should for any reason one pair of diagonally disposed brakes fail to act, the other pair will still act, *i. e.* in every case the vehicle will be braked on both sides.

Having now described my invention what I claim and desire to secure by Letters Patent of the United States is:—

1. In a road vehicle, the combination with two front and two rear road wheels, of braking devices connected to each of said wheels, connections interposed between the braking devices of each front wheel and the braking devices of the rear road wheel disposed at the opposite side of the vehicle, and manually controlled means, including a one-way clutch, adapted to actuate said interposed connections and to brake all the road wheels. 70

2. In a road vehicle, the combination with two front and two rear road wheels, of braking devices connected to each of the wheels, connections interposed between the braking devices for one front wheel and the braking devices for the rear road wheel at the opposite side of the vehicle, connections interposed between the braking devices for the second front road wheel and the braking devices for the second rear road wheel, a lever, and devices, including a one-way clutch, connecting said lever with said connections and adapted, on movement of said lever, to transmit movement to said connections and thereby to actuate all of said braking devices. 80

3. In a road vehicle, the combination with front and rear road wheels, of braking devices connected to each of the road wheels, a rotatable cross shaft freely mounted on the vehicle, a second cross shaft rotatable independently of said first cross shaft, means operatively connected to said first cross shaft and to the braking devices of one of the front road wheels and the braking devices of the rear road wheel disposed at the opposite side of the vehicle in relation to said front wheel, means operatively connected to said second cross shaft and to the braking devices of the other rear road wheel and to the braking devices of the other front road wheel, and manually controlled devices adapted to actuate said shafts and relative connections. 100

4. In a road vehicle, the combination with two front and two rear road wheels, of braking devices applied to the hub of each of said wheels, connections interposed between the braking devices of each front wheel and the braking devices of the rear road wheel disposed at the opposite side of the vehicle, a foot lever in operative relation with said connections and adapted on its movement to actuate all of said connections, a hand lever, and means operatively connecting said hand lever with said connections. 115

5. In a road vehicle, the combination with two front and two rear road wheels, of braking devices connected to each of the wheels, connections interposed between the

130

braking devices for each front wheel and the braking devices for the rear wheel at the opposite side of the vehicle, a foot lever in operative relation with said connections 5 and adapted on its movement to actuate all of said braking devices, a second lever, and devices connecting said second lever with said connections and adapted on movement of said second lever to transmit movement 10 to said connections and thereby to actuate all of said braking devices.

6. In a road vehicle, the combination with two front and two rear road wheels, of braking devices connected to each of the wheels, 15 connections interposed between the braking devices for one front wheel and the braking devices for the rear road wheel at the opposite side of the vehicle, connections interposed between the braking devices for the 20 second front road wheel and the braking devices for the second rear road wheel, a foot lever in operative relation with said connections and adapted on its movement to actuate all of said brake devices, a hand 25 lever, and devices including a one-way clutch connecting said hand lever with said connections and adapted on movement of said hand lever to transmit movement to said connections and thereby to actuate all 30 of said braking devices.

7. In a road vehicle, the combination with front and rear road wheels, of braking devices connected to each of the road wheels, a rotatable cross shaft freely mounted on the 35 vehicle, a rotatable tubular shaft disposed coaxially with and freely mounted in relation to said cross shaft, means operatively connected to said cross shaft and to the braking devices of one of the front road 40 wheels and the braking devices of the rear road wheel disposed at the opposite side of the vehicle in relation to said front wheel, means operatively connected to said tubular shaft and to the braking devices of the 45 other rear road wheel and to the braking devices of the other front road wheel, and manually controlled devices adapted to actuate said coaxially disposed shafts and relative connections.

50. 8. In a road vehicle, the combination with front and rear road wheels, of braking devices connected to the hub of each of said wheels, a rotatable cross shaft freely mounted on the vehicle, a rotatable tubular shaft 55 disposed coaxially with and freely mounted in relation to said cross shaft, a lever element movable with the cross shaft, a connection between said lever element and the braking devices of one of the front road 60 wheels, a second lever element movable with the cross shaft and terminating in a toothed sector, a pivoted toothed sector in mesh with said toothed sector, a connection between the pivoted toothed sector and the braking devices 65 of one of the rear road wheels dis-

posed at the opposite side of the vehicle in relation to the said front road wheel, a lever element movable with said tubular shaft and terminating in a toothed sector, a pivoted toothed sector in mesh with the last mentioned toothed sector, a connection between the last mentioned pivoted sector and the braking devices of the other rear road wheel, a connection between said tubular shaft and the braking devices of the other 70 front road wheel, a foot lever operatively connected to the said last mentioned pivoted sector, a hand lever freely mounted on said cross shaft, a catch device on said hand lever, a stationary toothed quadrant adapted to be engaged by said catch device, a compensating element freely connected to the first mentioned lever element movable with the cross shaft and to the lever and toothed sector element movable with said tubular 75 shaft.

9. In a road vehicle, the combination with two front and two rear road wheels, of braking devices connected to each of said wheels, rotatable spindles articulated to said braking devices, connections interposed between the spindle articulated to the braking device for one front wheel and the spindle articulated to the braking device for the rear road wheel at the opposite side of the vehicle, connections interposed between the spindle articulated to the braking device for the second front road wheel and the spindle articulated to the braking device for the second rear road wheel, and manually controlled lever, devices connecting said lever with said connections and adapted on movement of said lever to transmit movement to said connections and thereby to actuate all of said 90 braking devices, a second manually controlled lever and devices connecting said second lever with said connections. 95

10. In a road vehicle, the combination with two front and two rear road wheels, of braking devices connected to each of said wheels, rotatable spindles articulated to said braking devices, a rotatable cross shaft freely mounted on the vehicle, a second cross shaft rotatable independently of said first cross shaft, means operatively connected to 100 said first cross shaft and to the spindle articulated to the braking devices of one of the front road wheels and the spindle articulated to the braking devices of the rear road wheel disposed at the opposite side of the vehicle in relation to said front wheel, means operatively connected to said second cross shaft and to the spindle articulated to the braking devices of the other rear road wheel and to the articulated spindle of the braking 105 devices of the other front road wheel, and manually controlled devices adapted to actuate said shafts and relative connections. 110

11. In a road vehicle, the combination with two front and two rear road wheels, of 115

- braking devices connected to each of said wheels, a rotatable cross shaft freely mounted on the vehicle, a second cross shaft rotatable independently of said first cross shaft, connections interposed between said first cross shaft and the braking devices of one of the front road wheels and the braking devices of the rear road wheel disposed at the opposite side of the vehicle in relation to 10 said front wheel, connections interposed between said second cross shaft and the braking devices of the other front road wheel and the braking devices of the other rear road wheel, a foot lever in operative relation with all said connections and adapted to actuate all of said braking devices, a second lever, and devices connecting said second lever with all said connections and adapted to actuate all of said braking devices.
12. In a road vehicle, the combination with two front and two rear road wheels, of braking devices connected to each of the wheels, a set of connections interposed between the braking devices for one front wheel and the braking devices for the rear road wheel at the opposite side of the vehicle, a separate set of connections interposed between the braking devices for the second front road wheel and the braking devices for the second rear road wheel, a lever, and means connecting said lever with both said sets of connections and adapted on movement of said lever to transmit movement to said sets of connections and thereby to actuate all of said braking devices.
13. In a road vehicle, the combination with front and rear road wheels, of braking devices connected to each of the road wheels, 40 a rotatable element mounted on the vehicle a second rotatable element movable independently of said first rotatable element, means operatively connected to said first rotatable element and to the braking devices of one of the front road wheels and the 45 braking devices of the rear road wheel disposed at the opposite side of the vehicle in relation to said front wheel, means operatively connected to said second rotatable element and to the braking devices of the other rear road wheel and to the braking devices of the other front road wheel, and devices adapted to actuate said rotatable elements and relative connections.
14. In a road vehicle, the combination with two front and two rear road wheels, of braking devices connected to each of said wheels, connections interposed between the braking devices of each front wheel and the braking devices of the rear road wheel disposed at the opposite side of the vehicle, and means, including a clutch, adapted to actuate said connections and to brake all the road wheels.
15. In a road vehicle, the combination with two front and two rear road wheels, of braking devices connected to each of said wheels, rotatable spindles articulated to said braking devices, connections interposed between the spindle articulated to the braking device for one front wheel and the spindle articulated to the braking device for the rear road wheel at the opposite side of the vehicle, separate connections interposed between the spindle articulated to the braking device for the second front road wheel and the spindle articulated to the braking device for the second rear road wheel, and devices adapted to transmit movement to said connections and thereby to actuate all of said 80 braking devices.

In testimony whereof I have signed my name to this specification in the presence of two subscribing witnesses.

HENRI PERROT.
